ERECTION GAUGE

Alexander F. Blessing, near Newville, Pa.

Application July 24, 1939, Serial No. 286,290

2 Claims. (Cl. 33—180)

This invention relates to a gauge for use in the placement of posts and like, and particularly to insure the proper positioning of guard-posts along a highway.

5 In erecting guard-posts, it is desirable that they be vertical and located a uniform distance from the margin of the roadway.

The erection gauge of this invention constitutes a simple, accurate, economical, and easily 10 usable means for so setting the posts that they are placed at a uniform predetermined distance from the roadway margin and with their tops at a predetermined height above the roadway surface.

15 The invention also provides a gauge that is adjustable and usable conveniently to insure the vertical placement of the posts at a uniform distance from the roadway margin where grades on the berme are due to super-elevation on curves.

20 When considered with the description herein, characteristics of the invention are apparent in the accompanying drawing, forming part hereof, wherein embodiments of the invention are disclosed for purpose of illustration.

25 Like reference-characters refer to corresponding parts in the views of the drawing, of which—

Fig. 1 is a plan view, the gauge being shown in position against a post;

30 Fig. 2 is a side elevation of the gauge and a post, together with a fragmental cross section of a roadway and ground adjacent thereto;

Fig. 3 is a plan view of the lower part of the gauge, the posts and parts of the gauge being shown in section on the line 3—3, Fig. 2;

35 Fig. 4 is a side elevation of a modification.

In the drawing, A designates the roadway or paved surface of the highway, B ground at a side of the roadway, and C a guard-post.

40 For economy of manufacture and convenience of use, the principal members of the gauge usually are of angle iron as shown.

45 Referring to Figs. 1, 2, and 3, a base-bar of the gauge, which is horizontal or approximately so when the gauge is in use, is formed of two lapping members 5 and 6, which are relatively slideable for adjustment of the length of the bar. Each of these members has a longitudinal series 50 of equally-spaced holes 7, which accommodate bolts 8 that hold the members together at the desired length of the base.

55 A transverse foot member 9 is secured to the lower surface of the base member 5 near one end thereof at right angle thereto. The foot member 55 is adapted to abut and lie substantially parallel

to the margin of the roadway A when the part of the base member therebeyond (designated by 5—a) contacts with the upper surface of the roadway. The foot member may be sufficiently long to cause the base-bar to assume position 5 perpendicular to the roadway margin.

The other base member 6 has secured thereto near its free end a foot member 10 that extends laterally therefrom so that it may contact with the post when the part of that base member 10 therebeyond (designated by 6—a) also contacts the post.

An upright member 11 perpendicular to the base-bar is connected rigidly to member 6 at or near the foot member 10 and extends upwardly 15 therefrom.

A diagonal member 12 extends from the base member 6. The member 12 in its upper portion is bent to afford an extension 13 that is connected to the member 11 and extends therebeyond parallel to the base for contact with a side of the post directly above the base member part 6—a. The extension 13 has a foot 14 fixed thereto at the same distance from the upright 11 as the lower foot member 10 for contact with the post. 25 Thus, when the post contacts the two feet, it is parallel with the member 11.

A double level 15 is fixed in the angle of the extension 13 and the foot 14 opposite to the angle in which the post sets.

30 The base of the gauge is adjusted, by relative sliding of its members 5 and 6, to set the foot members 9 and 10 the distance apart corresponding to the distance from the roadway margin it is desired to position the guard-posts, and they 35 are held in that adjustment by the bolts 8.

When the base is placed with its foot member 9 against the margin of the roadway, a post to be set is placed against the feet members 10 and 14 and against the base member 6 and the extension 13. The gauge is held with its base horizontal, and its upright 11 thus is vertical, as indicated by the level 15, and consequently the post is vertical and at the predetermined distance 40 from the roadway.

45 When the gauge is to be used for the setting of posts with their tops a uniform distance above the roadway surface, the upright member 11 ordinarily is of the same length as that distance above the lower surface of the base of the gauge. 50 Accordingly, when a post has been driven until its upper surface lies in the same horizontal plane as the upper end of the upright member, its upper end is at the desired height. However, the upper end of the upright member may be 55

provided with a scale 16, to indicate lower desired positions of the upper ends of posts when it is desired to erect them of less height above the roadway surface.

- 5 Sometimes it is necessary, owing to various grades on the berme due to super-elevations on curves, to have adjustment in the gauge that will permit the base thereof to slant from the roadway surface below the horizontal, and at the same 10 time to permit adjustment of the upright member 11 to the true vertical and its maintenance in that position.

A gauge for use in these circumstances is exemplified by Fig. 4. As there shown, the base member 6 is connected pivotally to the upright member 11 as indicated at 17, and the diagonal member 12 similarly is connected to the upright member 11 as indicated at 18.

When it is necessary or desirable to deflect the 20 base of the gauge from the horizontal, the pivots permit the upright member 11 to be adjusted to the vertical as indicated by the level 15. The base member and the member 12 then are in such positions as shown by dotted lines in Fig. 4.

25 With this gauge, guard-posts may be set rapidly and accurately along a roadway. The gauge being held with the foot member 9 against the roadway margin and with its base kept horizontal, it is easy to place a post in the angles afforded by the base part 6-a and the foot member 10 and the extension 13 and the foot member 14, and thus the post is in vertical position. Guard

wires, cables, or like carried by the posts will lie substantially parallel with the roadway.

I claim:

1. A gauge comprising a base bar, an abutment on and extending laterally from said bar between the ends of the latter affording a lower angle with an end portion thereof into which work may be set, an upright member carried by said bar, an upper positioning structure carried by said member including work contacting members affording an upper angle in alinement with the lower angle, and spaced from the latter angle another abutment on said bar to contact a structure away from which the work is to be positioned. 10

2. A gauge comprising a base bar, an abutment on and extending laterally from said bar between the ends of the latter affording a lower angle with an end portion thereof into which work may be set, an upright member carried by said bar, 20 a diagonal brace extending from said bar connected to said upright member and having an upper terminal portion extending beyond said member and disposed in alinement with said bar, an abutment carried by said upright member 25 affording an upper angle with the upper terminal portion of said brace in alinement with the lower angle into which work may be set, and another abutment on said bar spaced from the lower angle to contact a structure away from which the 30 work is to be positioned.

ALEXANDER F. BLESSING.
